[57] CLAIM

The ornamental design for an automobile grille, as shown and described.

DESCRIPTION

FIG. 1 is a front perspective view of an automobile grille constructed in accordance with my new design and showing the relative location thereof as installed on an automobile; and,

FIG. 2 is an enlarged front elevational view thereof. It should be understood that the back side of my design is plain, unornamented and not visible during ordinary use. It should be further understood that the phantom lines showing in FIG. 1 are for illustrative purposes only and form no part of the subject invention.
